US0D1057868S

(12) **United States Design Patent** (10) **Patent No.:** **US D1,057,868 S**
(45) **Date of Patent:** **** Jan. 14, 2025**

(54) **TRAINING DEVICE**

- (71) Applicants: **Michael Pack**, Roswell, GA (US);
Charles Pack, Roswell, GA (US)
- (72) Inventors: **Michael Pack**, Roswell, GA (US);
Charles Pack, Roswell, GA (US)

(**) Term: **15 Years**

(21) Appl. No.: **29/755,270**

(22) Filed: **Oct. 19, 2020**

Related U.S. Application Data

- (60) Division of application No. 29/630,482, filed on Dec. 21, 2017, now Pat. No. Des. 899,535, which is a continuation of application No. 15/832,231, filed on Dec. 5, 2017, now Pat. No. 10,898,778.

(57) **CLAIM**

The ornamental design for a training device as shown and described.

DESCRIPTION

FIG. 1 is a front perspective view of a training device showing our new design;

FIG. 2 is a top perspective view of the training device of FIG. 1;

FIG. 3 is a bottom perspective view of the training device of FIG. 1;

FIG. 4 is a right side perspective view of the training device of FIG. 1;

FIG. 5 is a left side perspective view of the training device of FIG. 1;

FIG. 6 is a front elevational view of the training device of FIG. 1;

FIG. 7 is a rear elevational view of the training device of FIG. 1;

FIG. 8 is a right side elevational view of the training device of FIG. 1;

FIG. 9 is a left side elevational view of the training device of FIG. 1;

FIG. 10 is a top plan view of the training device of FIG. 1; and,

FIG. 11 is a bottom plan view of the training device of FIG. 1.

The broken lines having consistent short dash lengths (dash-dash-dash) are shown on the training device in FIGS. 1-11 forms no part of the claimed design.

1 Claim, 10 Drawing Sheets
